REVERSING MECHANISM

Frank H. Stolp, Geneva, N. Y.

Application August 9, 1946, Serial No. 689,316

5 Claims. (CL. 74—34)

1

The present invention relates to reversing mechanisms and more particularly to reversing mechanisms such as may be employed in reversing a carriage, table or similar part of a machine. In a more specific aspect, the invention relates to apparatus for tripping a reversing mechanism at the ends of the strokes of the carriage, table or other reversible part controlled thereby.

It is conventional practice to trip the reversing mechanisms of machines by a pivoted lever which is actuated at opposite ends of the stroke of the reversible part by adjustable stops carried by the reversible part. This requires sufficient overtravel of the carriage or table or other reversible part at the ends of its strokes for the stops to move the lever far enough to effect reversal. To reduce the amount of overtravel as much as possible, it has been customary to employ a spring load-and-fire mechanism so that when the lever has been swung in one direction or the other past center, the load-and-fire mechanism quickly moves it on to the end of its swing effecting shift of the reversing mechanism. A load-and-fire mechanism operates, however, with considerable shock, which causes noise, vibration and wear.

One object of the present invention is to provide means for tripping a reversing mechanism which will reduce to a minimum the amount of overtravel required to effect reversal.

Another object of the invention is to provide a trip for a reversing mechanism which will be just as effective as a load-and-fire actuated trip mechanism but which will not have to depend upon springs for operation and which will operate without shock.

Still another object of the invention is to provide a trip for reversing mechanisms which will not only effect operation of the reversing mechanism without shock, but achieve shift of the reversing mechanism with an easy start and easy stop motion.

Other objects of the invention will be apparent hereinafter from the specification and from the recital of the appended claims.

In the drawings:

Fig. 1 is a plan view of the carriage of a standard lathe or planer, showing a conventional form of reversing mechanism for the carriage, and showing trip apparatus constructed according to one embodiment of this invention mounted on the bed of the machine and connected to the reversing mechanism to operate the same at opposite ends of the travel of the carriage;

Fig. 2 is a fragmentary view in plan on an

2

enlarged scale showing the trip apparatus of this invention in process of actuation and in a different position from the position shown in Fig. 1;

Fig. 3 is another fragmentary plan view, showing the trip apparatus in still a further position, this position being one of its limit positions, reversal of the direction of movement of the carriage having now been effected;

Fig. 4 is a section through the trip apparatus on the line 4—4 of Fig. 2; and

Fig. 5 is a section taken on the line 5—5 of Fig. 3.

Referring now to the drawings by numerals of reference, 10 denotes the base or bed of a machine, such as a lathe or planer, on which the apparatus of the present invention is employed. 11 denotes a carriage which is mounted upon the bed 10 for reciprocation on ways 12.

In the machine illustrated, the carriage 11 is moved alternately in opposite directions through a conventional reversing mechanism comprising the gears 14 and 15 and the clutch member 16. The clutch member 16 is secured in any suitable manner to a shaft 17 which is journaled in the bed of the machine. Fastened to this shaft 17 is a spur pinion 18 which meshes with a rack 19 that is secured to the underside of the carriage 11. The gears 14 and 15 are adapted to be driven in opposite directions, and are engaged alternately with the clutch member 16 to drive the shaft 17 alternately in opposite directions. These gears are adapted to be driven from a main drive shaft 20, the gear 14 meshing with a spur pinion 21 which is secured to this drive shaft, and the gear 15 being adapted to mesh with a spur pinion 23 which is secured to a idler shaft 24 and which meshes with a spur pinion 25 that is secured to the main drive shaft 20. The gears 14 and 15 have clutch portions 30 and 31 formed integral with them which are adapted to be engaged, respectively, with the clutch teeth at opposite ends of the clutch member 16. For this purpose, the gears 14 and 15 are adapted to be moved axially of the shaft 17 to be shifted into and out of engagement with the clutch member 16.

The shifting of the gears 14 and 15 is effected by yoke members 32 and 33, respectively, which engage in grooves 34 and 35, respectively, formed in the hubs of the gears 14 and 15, respectively. The yoke members 32 and 33 are mounted upon a shift-rod 37 which is reciprocable axially in the bed of the machine. There are two collars 36 and 39 pinned to this rod and the yoke members 32 and 33 are held against these collars by coil

springs 40 and 41, respectively, which surround the rod 37 and which are interposed between the hub portions of the yoke members 32 and 33, respectively, and collars 42 and 43, respectively, that are pinned to the rod 37.

This is a conventional type of reverse mechanism and is widely used. The new feature of the invention is the means for shifting the rod 37.

Pivotedly mounted, as by means of the pin 52, upon a bracket 50 which is secured by screws 51 to the bed of the machine is a triangularly shaped plate 53. This plate has a pin 54 secured to it which is adapted to be engaged alternately at opposite ends of the stroke of the carriage 11 by the stops 55 and 56. These stops may be secured to the carriage by bolts 57 and may be adjustable thereon in the usual fashion to determine the length of stroke of the carriage.

The plate 53 carries another pin 59 on which is mounted a block 60. This block is adapted to engage in an elongated slot 61 formed in a lever 62. This lever fulcrums on a block 64 which is adapted to slide in the slot 61 and which is mounted upon a stud 65 that is secured in the bracket 50. At the end opposite that which is connected with plate 53, the lever 62 is pivotally connected by means of a pin 67 with a member 70 which is mounted to rotate on a stud 71 that is secured in the bracket 50. The member 70 has a hub portion whose periphery 72 is eccentric of the pivot stud 71. A ring member 74 surrounds the hub portion of the member 70 and has an arm 75 projecting from one side of it which is pivotally connected by a pin 76 with the head 77 of the shift rod 37. The eccentric member 70 is also formed with a relatively massive up-turned flanged portion 78 which serves as a weight.

In operation, assuming, for instance, that the carriage 11 is traveling in the direction of the arrow 80 of Fig. 1, the stop 56 is brought into engagement with the pin 54 of plate 53 just before the end of the leftward travel of the carriage, and in the further leftward movement of the carriage, the stop rocks the triangular plate 53 counterclockwise about its pivot pin 52 from the position shown in Fig. 1 to that shown in Fig. 2. Through engagement of the block 60 in the slot 61, this causes the lever 62 to rotate the eccentric member 70 with a slow start motion, but once movement of the crank member 70 is initiated, the weight and momentum of part 78 operates to carry crank member 70, lever 62 and plate 53 on to the ends of their movements. The carriage 11 continues to move in the direction of the arrow 80 until the crank member 70 has been swung through 180 degrees from the position shown in Fig. 1 to the position shown in Fig. 3. The swing of the eccentric member 70 effects axial movement of the shift rod 37, causing the clutch member 30 and its gear 14 to be moved out of engagement with the clutch member 16 and the clutch member 31 and its gear 15 to be moved into engagement with clutch member 16. Thus, the carriage 11 is reversed. The shift of rod 37 takes place without shock because toward the end of its movement, eccentric member 70 is slowed down because of the eccentric connection of lever 62 therewith.

Toward the opposite end of movement of carriage 11, the stop 55 strikes the pin 54 and the triangular shaped member 53 is swung clockwise about its pivot pin 52, causing the lever 60 to reverse the eccentric member 70 and swing it from the position shown in Fig. 3 back to the position shown in Fig. 1, again reversing the

direction of drive to the carriage. In its swinging movement, the eccentric member 70 is again started easily with a slow start motion, but this motion being a crank motion is speeded up and the weight of part 78 carries it on to quickly effect the reversal. Toward the end of the swing of the member 70, however, the motion is again slowed down as the member 70 approaches its stop position.

The apparatus of the present invention, therefore, provides a slow start and slow stop motion for shifting a standard reverse mechanism. Moreover, through use of weight 78 the trip mechanism effects rapid shift of rod 37 once it has been started. Overtravel of carriage 11 at either end of its stroke is, therefore, reduced to a minimum.

While the apparatus has been shown in connection with a particular form of reverse mechanism of the mechanical type, it will be understood that it may be applied to the shifting of any form of reverse mechanism, whether mechanical, or fluid-pressure operated or of any other type. In a fluid-pressure operated reverse mechanism, for instance, where reversal is effected by shifting of a valve, the apparatus of the present invention will effect slow start and slow stop motion of the valve in its reversing movement and at the same time will minimize the over-travel of the carriage or other reciprocating part.

It will further be understood that while the invention has been described in connection with a particular embodiment thereof, it is capable of further modification and this application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. The combination with a reciprocable part, means for moving said part in opposite directions, and means for reversing said last named means, of a movable member which is connected to the reversing means and which is operable when moved through a given distance to effect operation of the reversing means, means carried by the reciprocable part for initiating movement of the movable member toward the ends of the stroke of the reciprocable part, and means carried by the movable member for causing it to be moved on through the given distance once its movement has been initiated in one direction.

2. The combination with a reciprocable part, means for moving said part in opposite directions, and means for reversing the last named means to effect alternate movement of the reciprocable part in opposite directions, of means for tripping the reversing means comprising a ring member connected to the reversing means, an oscillatable member on which the ring member is journaled with its axis eccentric of the axis of the oscillatable member, a pair of spaced stops on the reciprocable part for swinging the oscillatable member in opposite directions at opposite ends of the stroke of the reciprocable part, and a weight carried by the oscillatable member and radially off-set from the axis of said member, said weight being sufficient to urge said member on to the end

of its movement once its movement has been initiated.

3. The combination with a reciprocable part, means for moving said part in opposite directions, and means for reversing the last named means, of means for tripping the reversing means comprising an oscillatable member, a ring member journaled on the oscillatable member and connected to the reversing means, means for swinging the oscillatable member in opposite directions at opposite ends of the stroke of the reciprocable part comprising a pair of spaced stops secured to the reciprocable part, a rockable plate adapted to be rocked in opposite directions, respectively, on engagement of the stops therewith, and a pivoted lever connected at one end to the plate and at its opposite end to the oscillatable member.

4. The combination with a reciprocable part, means for moving said part in opposite directions, and means for reversing the last named means, of means for tripping the reversing means comprising an oscillatable member, a ring member journaled on the oscillatable member and connected to the reversing means, means for swinging the oscillatable member in opposite directions at opposite ends of the stroke of the reciprocable part comprising a pair of spaced stops secured to the reciprocable part, a rockable plate adapted to be rocked in opposite directions, respectively, on engagement of the stops therewith, a pivoted lever connected at one end to the plate, and at its opposite end to the oscillatable member, and

a weight secured to the oscillatable member at a point off-set from its axis.

5. The combination with a reciprocable part, means for moving said part in opposite directions, and means for reversing the last named means to effect alternate movement of the reciprocable part in opposite directions, of means for tripping the reversing means comprising an oscillatable member, a ring member journaled on the oscillatable member and connected to the reversing means, a pair of spaced stops secured to the reciprocable part, a rockable plate adapted to be rocked in opposite directions, respectively, on engagement of the stops therewith, a pivoted lever having a slot therein, a pin and block slideable in said slot for connecting the lever at one end to the rockable plate, means for connecting the lever at its opposite end to the oscillatable member, and a weight secured to said oscillatable member eccentrically of the axis of said member.
